UNITED STATES PATENT OFFICE.

ROBERT ADAMS, OF 17 BLACKMAN STREET BOROUGH, COUNTY OF SURREY,
ENGLAND.

WINDOW.

SPECIFICATION forming part of Letters Patent No. 310,355, dated January 6, 1885.

Application filed June 7, 1884. (No model.) Patented in England March 15, 1884, No. 4,934.

To all whom it may concern:

Be it known that I, ROBERT ADAMS, a subject of the Queen of Great Britain, residing at 17 Blackman Street Borough, in the county 5 of Surrey, England, engineer, have invented certain new and useful Improvements in Convertible Window - Sashes, (for which I have obtained a patent in Great Britain, No. 4,934, dated March 15, 1884,) of which the following is a specification.

My improvements relate to sliding sashes of windows which are capable of being converted into swing - sashes for convenience in cleaning or repairing, and also for purposes 15 of ventilation. I divide the sash-stile vertically on each side, at or near the level of the bead, into two parts. One part fits into the ordinary groove formed by beads, and is guided in its vertical motions in such groove 20 by the front, back, and parting beads. The two portions of the stile are united at or near the center, or at any other convenient part, by a pivot forming a swing - center. The sliding portion of the stile is fitted with the 25 usual window-cord, to which the usual balance-weight is attached.

In the accompanying drawings, Figure 1 is a horizontal section of a window-casing and two sashes fitted therein, showing my invention 30 applied thereto. Figs. 2 and 3 are detail sectional views of the means for locking the swinging sash-section of the sliding stile. Figs. 4 to 8, inclusive, are other detail views. *a a* is the upper sash in section. *b b* is the 35 upper side of the lower sash. *c c* are the sash-weights. *d d* are the lines which show where the sash-stile is divided into two vertical parts, and *e²* are the central pivots for connecting said divided stile and allowing one part to 40 turn upon the other. Springs *g g* are fitted on said center pivots to separate or throw apart the two portions of the stiles when it is desired to swing the sash on its centers. The action of the spring is counteracted by the 45 eccentric lever *h*, which is pinned to the center pivot, *e²*. When the lever *h* is raised, as shown in Fig. 2, the two parts of the stile are separated, and when the lever *h* is lowered, as shown in Fig. 3, the two portions are drawn

together and the spring *g* is compressed. 50 This arrangement may also be used without the spring, as it is generally found to release the sash sufficiently when the lever *h* is raised.

In Fig. 4 is shown a draft - stop, which is held in its place by one or more springs in the 55 groove *m*, which keeps the stop *n* in the groove *m'*; but when the sash is rotated the stop is compelled to yield, the springs allowing it to recede into the groove.

Fig. 5 shows another form of draft - stops, 60 which may be used in conjunction with the pivots shown in Figs. 1, 2, and 3, the two parts of the stile being separated before swinging the sash. One stop only may also be used.

Fig. 6 shows two forms of hook for the 65 purpose of keeping the portions of the sash-stile together. This is generally applied near the top or bottom of the stile; and Fig. 7 shows another mode of keeping the two parts of the stile together, applicable to the ends of 70 the stile. A staple, *o*, is inserted, as shown, a side view of the same staple being shown below the figure, which staple being driven in retains the parts draft-proof.

Fig. 8 shows another method of drawing together the two portions of the sash-stile, which is effected in the act of closing the sash. The tongue *p* clinches the slip *r*, and thereby draws the two portions into close contact. 75

I claim—

1. In convertible window - sashes, the combination of the pivots or center-pins *e²* and eccentric lever *h* with the divided sash-stile or duplex frame, substantially as set forth.
2. In convertible window - sashes, the combination of the pivots or center-pins *e²*, the encircling springs *g*, and eccentric levers *h* with the divided sash-stile or duplex frame, substantially as herein set forth.

In testimony whereof I have hereunto set 9 my hand this 26th day of May, 1884.

ROBERT ADAMS.
